UNITED STATES PATENT OFFICE.

JAMES B. CARY, OF MASON CITY, IOWA, ASSIGNOR OF ONE-THIRD TO CLAXTON W. LACY, OF DES MOINES, IOWA, AND ONE-THIRD TO CHARLES J. RAFFENSPERGER, OF VICTOR, IOWA.

MAIL CATCHING AND DELIVERING APPARATUS.

1,223,852.

Specification of Letters Patent. Patented Apr. 24, 1917.

Application filed March 3, 1916. Serial No. 81,863.

To all whom it may concern:

Be it known that I, JAMES B. CARY, a citizen of the United States, residing at Mason City, in the county of Cerro Gordo 5 and State of Iowa, have invented certain new and useful Improvements in Mail Catching and Delivering Apparatus; and I hereby declare that the following is a full, clear, and exact description thereof, reference being had to the accompanying drawings, which form part of this specification.

My present invention is a novel improvement in mail delivery and receiving apparatus of the general type shown in my Patent No. 976,433 dated November 22, 1910; and the object of such invention is to enable the mail to be safely taken at the receiving point, and to be discharged safely automatically at the desired point; and the 15 invention provides novel means for catching mail; novel means for discharging mail; novel means for operating the discharger by air pressure; novel tripping mechanism for tripping the discharging means; and various 20 other novel minor details of construction and combination of parts, all of which will be hereinafter more fully described with reference to the accompanying drawings, so that others skilled in the art will be able to 25 construct and use the invention; and the essential features and combinations of parts for which protection is desired are summarized in the appended claims.

In said drawings:—

Figure 1 is a detail sectional elevation of part of a mail car showing the receiving and discharging devices in elevation.

Fig. 2 is an enlarged detail view of the air cylinder and connections for operating 40 the discharger.

Fig. 3 is a detail view of the air valve.

Fig. 4 is an enlarged detail view of part of the discharger operating devices.

Fig. 5 is an enlarged vertical sectional 45 elevation of the discharging mechanism and catching devices.

Fig. 6 is an enlarged sectional view of Fig. 5.

Fig. 7 is a detail sectional plan view of Fig. 6. 50

Fig. 8 is a detail.

Fig. 9 is a detail sectional view of the mail catcher.

The mail catching and delivering devices are adapted to be applied to an ordinary 55 mail car, and are intended to be substantially duplicated at each side of the car, but a description of one set of such devices will suffice to explain all.

In the accompanying drawings the car 60 door 1 of ordinary construction is adapted to be normally held in closed position by means of a pivoted catch 2 engaging a lug 1^a on the door, and held in normal engagement with the lug by means of a spring 2^a, 65 or other suitable device. The door is adapted to be opened, when released by the catch, by any suitable means, as for instance a cable or chain 1^c attached to the door and to a spring actuated drum of an ordinary 70 type contained in a casing 1^d attached to the inside of the car. Any preferred means for opening the door quickly when released may be employed.

Adjacent each side of the door opening 75 and within the car are mounted vertically disposed preferably hollow shafts 3 which may be supported at bottom on disks 3^a preferably mounted by roller bearings upon bases 3^b suitably bolted to the car floor. The 80 upper end of each shaft 3 may be journaled in any bearings, as in brackets 3^c, attached to the side of the car. Preferably each shaft 3 is provided on its upper end with a sprocket 3^d rigidly attached thereto in any 85 suitable manner and provided with a hub 3^e on its upper end engaging bracket 3^c as indicated in Figs. 5 and 6. I do not however restrict myself to any particular construction of said shafts or means for journaling same in place, the essential object being to provide a rotatable support for the mail discharger at each side of the door opening so that the discharger can be operated from either support. 90

The sprockets 3^d on the adjacent shafts 3 95

are engaged by a sprocket chain 3ⁱ (Fig. 4) the ends of which are connected to the opposite ends of a piston rod 4^b extending through an air cylinder 4 (Fig. 2), a piston 5 4^a being fast on the rod within the cylinder, so that if the piston is moved in either direction the chain will be shifted and consequently shafts 3 rotated.

The opposite ends of the cylinder 4 are 10 connected by pipes 4^c to one of the ports of a valve 4^e, another part of which connects with an air pipe 4ⁱ. The valve 4^e has an intermediate vent port 4^f, and said valve is operable by means of a valve lever 4^g which 15 depends below the cylinder 4 and lies adjacent the inner upper edge of the door 1. The valve 4^e is preferably normally closed by means of a spring arranged in any suitable manner, a spring 4^h being indicated 20 in Fig. 3 of the drawings for this purpose.

Venting valves 4^d of any suitable construction may be interposed in the pipes 4^c between the cylinder 4 and valve 4^e, said valves 4^d should be so constructed that either 25 end of the cylinder 4 may be cut out of communication with valve 4^e by closing the related valve 4^d, and when such communication is closed the corresponding end of the cylinder 4 is vented through such valve 4^d 30 as indicated in Fig. 2. Thus in the example illustrated in Fig. 2 when the valve 4^e is opened air may be admitted from pipe 4ⁱ to the left hand end of the cylinder 4 so as to drive piston 4^a to the right, and air may be 35 simultaneously vented from the right hand end of cylinder 4 through the valve 4^d; but when the lever 4^g returns to normal position closing valve 4^e the left hand end of the cylinder is vented through the vent opening 4^f 40 in valve 4^e, see Fig. 2. If the left hand valve 4^d was closed and the right hand valve 4^d opened, then compressed air would be admitted into the right hand end of the cylinder 4 when the valve 4^e was opened.

45 The lever 4^g as stated is adapted to be operated by means of a suitably constructed catch 1^g on the door 1, which catch is arranged in position to engage lever 4^g as the door opens and open the valve 4^e. On the 50 opening movement of the door catch 1^g first engages lever 4^g and opens the valves and then the door continues to open and eventually disengages the valve whereupon the spring 4^h immediately returns lever 4^g to 55 normal position and closes the valve 4^e. Upon its return movement the catch 1^g should pass the lever 4^g in the position indicated in Fig. 1; for this purpose catch 1^g may be provided with a pivoted dog 1^h 60 which will engage and move lever 4^g forward when the door opens, but upon the return movement of the door the dog 1^h will turn on its pivot and pass under lever 4^g and then return same to engaging position.

Any suitable catch or construction may be 65 used which will enable the door to operate lever 4^g on its opening movement to return past lever without shifting same upon closing of the door.

The pipe 4ⁱ may be connected with vertically disposed pipes 4^j at each end which pipes 4^j may pass down through the hollow shaft 3, as shown, and are connected at their lower ends with an air tank 5 of any suitable construction secured to and below the car floor. This tank 5 may be connected by a pipe 5^a with the usual storage tank of the air brake apparatus on the car. Preferably a valve 5^c is placed in the pipe 5^a having a minute opening therein so that while air can 80 be supplied to cylinder 5 until the pressure therein equals that in cylinder 5^b yet the sudden outlet of air from cylinder 5 caused by the opening of valve 4^e will not disturb the air pressure in cylinder 5^b in such a 85 manner or cause any such release of air from the air brake apparatus as might affect the proper working thereof.

The mail discharger is preferably detachably attachable to either shaft 3; the discharger is shown as composed of a frame having a lower member 6 and an upper member 6^a connected with the member 6 at its forward end, and a brace member 6^b connecting members 6, 6^a, and a pouch receiver 90 or holder 6^c, attached to the outer end of member 6. The free end of member 6^a may be hooked, as shown at 6^d, Fig. 7, so that it can be detachably engaged with shaft 3, and may be supported thereon by a collar 3ⁱ 95 attached to said shaft. The adjacent end of member 6 is bifurcated, as shown at 6^e (Fig. 8) and is adapted to engage a diametrically disposed rib 3^f on the upper face of the bearing block 3^a at the lower end of the 100 shaft 3, and when engaged therewith may be secured by a bolt 6^g so as to detachably fasten it in place; and it may be held down on the bearing 3^a by a collar 3^j, adjustably attached to the shaft 3. By removing bolt 105 6^g and raising collar 3^j the discharger can be raised and disengaged from the shaft 3, and can be reengaged therewith when desired. The discharger 6^c may be pivoted on the member 6 as described in my aforesaid 110 patent, so that it can be turned to face in either direction.

The latch 2 is preferably automatically tripped when it is desired to release the door by suitable means, operated if desired from the outside of the car. As shown in the drawings to the rear end of the latch 2 is connected a spring 2^c to which are attached chains 2^d respectively attached to the ends of an arm 2^e secured to the upper end of a tubular member 2^f pivoted at 2^g on a plate attached to the bottom of the car and depending through a slot in the car bottom as 115 120 125

indicated in Fig. 1. Through this member 2^f depends a rod 2^h provided with a handle 2ⁱ on its upper end by which it can be raised, if it is not desired to have the tripping mechanism operate; when it is desired to have the tripping mechanism operate rod 2^h is lowered to the position shown in Fig. 1. The lower end of this rod is thus adapted to contact with a suitable stop attached to the rail or track adjacent the point where it is desired to have mail discharged. This trip may be a pivoted plate 2^m upheld in normal position by springs 2ⁿ see Fig. 1, or it may be a segmental shaped plate 2° attached to the sleepers as indicated in Fig. 1. The invention is not restricted to any particular member on the track for engaging the trip 2^h; but when the rod 2^h is in lowered position as indicated in Fig. 1 and the car is moving in the direction of the arrow Fig. 1 if the trip 2^h engages trip 2^o, or trip 2ⁿ, the lever 2^f will be rocked on its pivot 2^s and this rocking of the lever will rock head 2^e and cause one of the chains 2^d to pull latch 2 down and release the door 1^a whereupon the door operating devices will open the door and the mail will be discharged as hereinafter explained.

The mail catcher 7 is of the general ordinary type and is slidably mounted on a bar 7^a; the sleeve portion 7^b of the catcher, by which it is mounted on rod 7^a, is provided with a lateral tubular projection 7^c through which passes a rod 7^d which is adapted to project through an opening in the sleeve 7^b and across the bight of the catcher as indicated in dotted lines in Fig. 9. The rod 7^d is normally held in retracted position by means of a plate 8, which is slidably mounted on the sleeve 7^b but is provided with an opening 8^a which may be brought into register with the end of the rod 7^d by sliding the plate 8. When the opening 8^a comes into register with rod 7^d the latter will be projected by means of springs 7^e. When the catcher is to be placed in position to engage the mail sack, in the ordinary manner, the rod 7^d is retracted and slide 8 adjusted so as to hold it in retracted position. The slide 8 however is provided with a finger 8^b which projects into the bight of the catcher and is adapted to be struck by the bag of mail, when the latter is caught, and moved thereby so as to bring opening 8^a into register with rod 7^d whereupon spring 7^e projects rod 7^d across the bight of the catcher and holds the bag in the catcher until it is removed by the mail clerk.

The catcher may be held in position to engage and take a mail sack in any suitable manner. As shown a member 9 can be engaged with an eye 7^a on the catcher and with a suitable retainer on the car as indicated in Fig. 5. This spring tends to turn

the catcher on rod 7^a, into sack-taking position; and when the door is open the catcher may be arrested in sack-taking position by a chain 9^a attached to the projection 7^e and to a suitable retainer on the car above the catcher as indicated in Fig. 5. The door may be provided with a metal strip to protect it from abrasion by contact with the handle or end 7^o of rod 7^c, if desired as in Fig. 5. The cylinder 4 may be suspended within the car, above the door, in any suitable manner, as by means of brackets 4^p as indicated in the drawings.

Operation.

When it is desired to catch a sack of mail the catcher is set in the usual manner but the rod 7^d is retracted and the slide 8 projected so as to hold this rod in retracted position as above described. If it is desired to discharge mail the discharger frame is attached to the proper shaft 3 according to the direction in which the car is moving and if the car be moving to the left the discharger should be attached to the right hand shaft 3 as indicated in Fig. 1, the mail discharger being in about the position indicated in Fig. 6 or substantially at right angles to the car door, which is closed. The mail sack, or mail to be discharged, is placed in the holder 6^c; then the trip 2^h is adjusted when the car nears the point of discharge and when the trip 2^h is engaged by the device on the track so as to rock lever 2^e the catch 2 is caused to disengage the door and the latter is thrown open and thereby through catch 1^g engages valve lever 4^g and opens valve 4^e as the door opens. This immediately admits compressed air into the cylinder 4 (valves 4^d having been previously adjusted by hand so that air is admitted for example into the left hand end of the cylinder) and consequently the piston 4^a is moved to the left or in the direction in which the car moves which turns shafts 3 to the right or clockwise, and thus swings the discharger rapidly around clockwise so that it projects out of the car door opening and discharges the mail rearwardly, or in a direction opposite to that in which the car is moving; the outward swinging movement of the discharger may be arrested when the discharger is approximately at right angles to the car body by any suitable means. As shown the discharger is provided with a bumper 6ⁿ which is adapted to engage the side of the car jamb or a suitably located stop and arrest the discharger at the proper time. The discharger is operated rapidly, and the mail will be discharged rearwardly with sufficient momentum to largely, if not entirely, offset its forward movement with the car; and thus the mail is not as liable to be injured as it would be if the mail was

thrown out at right angles to the car. If the car is moving in the opposite direction (to the right) the discharger can be easily attached to the left hand shaft 3 and the 5 valves 4^a turned so that air will be admitted into the proper end of the cylinder 4 to rotate the discharger in the desired direction. The shafts 3 and their connections are preferably duplicated at both sides of the door, 10 and at both sides of the car, but the detachable and attachable discharger may be used in connection with any of such shafts.

What I claim is:

1. In combination with a car having a 15 door, a mail discharger, and means for operating said discharger including a cylinder, means for supplying air to said cylinder, a valve for controlling the admission of air to said cylinder and means on the 20 car door for automatically opening said valve when the door opens.

2. In combination a mail discharger, and means for operating said discharger including an air cylinder means for supplying 25 air to said cylinder, a valve for controlling the admission of air to said cylinder and devices for operating said valve upon the opening of the car door, with a catch for holding said door normally in closed position, and tripping mechanism for releasing 30 said catch.

3. In mail discharging apparatus, the combination of a rotatable shaft, a discharger, an air cylinder, a piston therein, 35 means connected with said piston for turning said shaft, and a valve for controlling the admission of air to and from said cylinder, with a catch on the car door, a valve lever adapted to be engaged by said catch 40 to open the valve when the door opens; means for normally holding the door in closed position, and means for opening the door when disengaged by the catch.

4. In mail discharging apparatus, the 45 combination of a rotatable shaft, a discharger, an air cylinder, a piston therein, means connected with said piston for turning said shaft and a valve for controlling the admission of air to and from said cylinder, with a catch on the car door, a valve 50 lever adapted to be engaged by said catch to open the valve when the door opens; means for normally holding the door in closed position, and means for opening the door when disengaged by the catch, trip devices for disengaging the catch, and a relatively fixed device on the track adapted 55 to actuate the trip devices.

5. In mail discharging apparatus, the 60 combination of a rotatable shaft, a discharger, an air cylinder, a piston therein, means connected with said piston for turning said shaft, means for supplying compressed air to said cylinder, a valve for con-

trolling the admission of air to and from 65 said cylinder, a lever for operating said valve, a catch on the car door adapted to engage said lever and open the valve when the door opens, means for normally holding the door in closed position, means for 70 opening the door, trip devices for disengaging the catch, and a relatively fixed device on the track adapted to actuate the trip devices.

6. In a mail discharging apparatus, the 75 combination of a pair of tubular shafts at opposite sides of a door opening, a discharger detachably attachable to either shaft, an air cylinder, a piston thereon, and connections between said cylinder and said 80 shafts for rotating the latter; pipes connecting said cylinder with a compressed air supply; and a controlling valve for regulating the admission of air to said cylinder, and a trip on the car door adapted to actuate the valve when the door opens.

7. In mail discharging apparatus, the combination of tubular shafts at opposite sides of a car door opening, a discharger 90 operable by either of said shafts, an air cylinder, a piston thereon, and connections between said cylinder and said shaft for rotating the latter; pipes connecting said cylinder with a compressed air supply, and a valve for controlling the admission of air 95 to said cylinder, a trip on the car door adapted to actuate said valves when the door opens, a catch for normally holding the door closed, and trip devices for disengaging the catch from the door, and means 100 for throwing open the door when released.

8. In a mail discharging apparatus, the combination of a pair of tubular shafts at opposite sides of a door opening, a discharger detachably attachable to either 105 shaft, an air cylinder, a piston thereon, and connections between said cylinder and said shafts for rotating the latter; pipes connecting said cylinder with a compressed air supply; and a controlling valve for regulating the admission of air to said cylinder, and a trip on the car door adapted to actuate the valve when the door opens, a catch for normally holding the door closed, 110 means for throwing open the door when released, trip devices for disengaging the catch from the door, and a stationary device beside the track adapted to operate the trip devices.

9. A mail discharging apparatus comprising a rotatable vertically disposed shaft located within the car and beside the car door opening; a discharger mounted upon said shaft and adapted to be swung thereby, an air cylinder adjacent the shaft, 115 a piston in said cylinder, means actuated by the said piston for turning said shaft, means for supplying air to said cylinder, 120 125

valves for controlling the admission of air to said cylinder, and means for controlling said valves and means to prevent the operation of the discharger when the door is closed.

10. A mail discharging apparatus comprising a pair of rotatable vertically disposed shafts located at opposite sides of the car door and within the car, a discharger attachable to either shaft, an air cylinder above the car door, a piston in said cylin-

der, means actuated by the said piston for turning said shaft, means for supplying air to said cylinder, a valve for controlling the admission of air to said cylinder, and means 15 for controlling said valve and means to prevent the operation of the discharger when the door is closed.

In testimony that I claim the foregoing as my own, I affix my signature.

JAMES B. CARY.
